CLAIM

The ornamental design for a security light, as shown and described.

DESCRIPTION

FIG. 1 is a front elevation view of a security light showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view of the security light in which a cover of the security light is open and the lights are repositioned;

FIG. 10 is a front elevation view of the security light in which the cover of the security light is open and the lights are repositioned; and,

FIG. 11 is a top plan view thereof in which the cover of the security light is open and the lights are repositioned.

(Continued)

The broken lines shown in the drawings are for the purpose of illustrating portions of the article that form no part of the claimed design.
